REFRIGERATION SYSTEM

Ragnar A. Norbom, Alexandria, Va.

Application June 13, 1952, Serial No. 293,284

3 Claims. (Cl. 62—117.65)

1

This invention relates to refrigeration systems and, although useful to cool any chamber, has special application to refrigeration systems adapted for use upon vehicles for the transportation of perishable commodities such as foods, drugs, etc.

To date, there is no known system of mechanical refrigeration devised for railroad cars which has enjoyed any substantial degree of commercial success. As a result, even today, the largest users of refrigerating equipment for railroad cars continue to depend for cooling, upon ice stored in space-consuming bunkers, positioned at various locations within a refrigerator car. The problems involved in adapting mechanical refrigeration systems to the needs of this industry are many. Quite frequently refrigerator cars must stand for long periods in locations where the ambient temperature places a heavy demand on the refrigerating system. Obviously, such devices as compressors driven either directly from the axles of the cars or through electric energy supplied by generators driven from the axles, are not well suited for use on standing cars where other electricity is unavailable.

Absorption type refrigeration systems have been tried, but with very limited success. The drawbacks to these systems apparently include the fire hazard due to the flame and the problem of keeping a burner flame lighted in a closed or drafty moving vehicle. Other attempts at solving the instant problem have included refrigeration systems of the type in which a high pressure tank of refrigerant has been allowed to expand slowly into an evaporator coil placed within the car, and then been exhausted to the atmosphere. Such systems are expensive in view of the waste of refrigerant and are impractical because of the large quantity of refrigerant which must be carried to maintain desired temperatures on long hauls where renewals are not purchasable.

This invention embodies an entirely novel approach to many problems in all kinds of mechanical refrigeration systems. In part, this invention utilizes the heat (energy) extracted from the lading space to reduce the power input necessary to operate the system. In addition, this invention also utilizes the kinetic energy of the liquid refrigerant circulating in the system to further reduce the power input requirements. While the principles of this invention are also applicable to other types of mechanical refrigeration, it will be described herein with particular reference to a system adapted for use on railroad refrigerator cars, or refrigerated highway vehicles.

2

In conventional mechanical refrigeration systems, the heat abstracted from the lading space is wasted. In a domestic type refrigerator, for example, the condenser is simply exposed to the ambient air so that the heat content of the refrigerant due to heat pickup in the lading space plus the heat of compression is dissipated through the condenser to the ambient air.

It is a primary object of this invention to provide a means for converting this otherwise wasted heat into useful energy to assist in the circulation of refrigerant through the system.

It is a further object of this invention to eliminate from the system apparatus which would serve to function as a conventional condenser, at least insofar as from such condenser the heat absorbed by the refrigerant in the evaporator would be lost to atmosphere.

A further object of the invention is to utilize a direct heat exchange between liquid refrigerant which has by-passed the evaporator and gaseous refrigerant which is withdrawn from the evaporator to effect condensation of the gaseous refrigerant and thus retain the heat (which otherwise would be wasted) to effect a saving in the required energy input to the system as a whole.

Another object of this invention is to provide pressure booster means, operating automatically when and as occasioned by waning pressure of the refrigerant vapor, by which means another gas, under pressure independent of and not in contact with the refrigerant vapor, will move a piston to compress, and augment the pressure of such vapor and restore thereto the energy lost through friction or otherwise, so that such refrigerant vapor will continue to cause the liquid refrigerant to circulate throughout the system.

This invention will be fully understood from the following description read in conjunction with the attached drawings in which:

40. Figure 1 is a diagrammatic showing of the overall system, and

Figure 2 is a detailed sectional side elevation of the gas operated pressure booster which supplies, automatically when from time to time required, such additional energy as becomes necessary to keep the system operating.

Referring now to Figure 1, the basic refrigerant circuit includes a tank 10, for the storage of at least such quantity of refrigerant as the system requires, leaving space thereabove, substantially as shown. While several known refrigerants would operate satisfactorily in this system, it is contemplated that use will be made primarily of Freon 12 or its equivalent. From the lower 50 portion of the tank 10, a conduit 11, for liquid

refrigerant, connects to the high pressure inlet of an ejector device 12. Interposed in this conduit 11 are a filter 13 and a valve 14. The purpose of the latter will be described hereinafter. From the Venturi outlet of the ejector device 12, a conduit 15 conducts refrigerant to a coil 16 and a further conduit 17 connects the other side of the coil through a check valve 18 to a nozzle 19 which enters the tank 10. An evaporator 20, in the lading space to be cooled, is connected in parallel with conduit 11. The inlet to the evaporator is through a conduit 21 and an expansion valve 22. The outlet of the evaporator is connected to the suction inlet of the ejector 12.

Liquid refrigerant is caused to circulate in the system by pressure of its own vapor in tank 10. It will flow from tank 10 through the conduit 11 and the valve 14. When the refrigerant reaches the junction point of conduits 11 and 21 the flow will divide, and part will pass through the expansion valve 22 into the evaporator where it becomes a vapor, such change of phase absorbing heat from the lading space. The remainder of the refrigerant liquid will continue through conduit 11 to the ejector. The liquid refrigerant flowing through the ejector will then serve to withdraw and entrain cold gaseous refrigerant from the evaporator, and the mixture will be returned through the conduit 15, coil 16, conduit 17, check valve 18 and nozzle 19 to the tank 10. In its passage from the ejector 12, to the tank 10, the vapor component of the mixture will revert to liquid phase as next described.

Important reactions in this refrigerant cycle are those which take place between the ejector device 12 and the check valve 18. The liquid refrigerant leaving the ejector will be at substantially ambient temperature, but the gaseous refrigerant will be at a much lower temperature. Initially, therefore, the gaseous phase is warmed to some extent by its direct contact with the liquid refrigerant, and the latter is cooled, so that the temperatures of the two phases tend to approach a common intermediate degree with relatively reduced pressure. The latter temperature, of course, will be determined by the relative proportions of liquid refrigerant fed through the conduit 11 to the ejector 12 and of that portion which flows through the conduit 21 into the evaporator. The rapidly moving stream of liquid refrigerant leaving the ejector 12 develops kinetic energy due to its mass and velocity. This creates a build-up of pressure in the coil 16 because the flow backs up from the check valve 18, held by the opposing vapor pressure in tank 10. The immediate and instantaneous result of this pressure build-up is that the gaseous phase of the refrigerant in the mixture is quickly raised in temperature while the temperature of the liquid portion of the refrigerant in the mixture remains substantially constant. With a temperature differential thus created between the gaseous and liquid phases of the refrigerant and with both phases in mutual contact, the gaseous phase will entirely condense. In so doing the gaseous phase gives up its latent heat of condensation to the liquid phase, increasing the temperature of and energy in the liquid. The resulting total pressure now accumulated in coil 16 will overbalance the pressure of refrigerant vapor in tank 10 and open check valve 18, through which and through nozzle 19 the liquid will re-enter tank 10, completing the operating cycle.

The remainder of the apparatus shown in Figure 1 is entirely for the purpose of maintaining

a predetermined pressure within the tank 10. The source of additional pressure therefor, as will be apparent from an examination of the drawing, is the high pressure cylinder 23 which may contain an inert gas such as carbon dioxide or helium. A pressure booster 24 operates automatically, partly by pressure from the cylinder 23, to increase the pressure of gaseous refrigerant in the top of tank 10.

Referring now to Figure 2 for details of the pressure booster 24 it will be seen that it comprises essentially a cylinder 25 and a piston 26 slidably mounted therein. Assuming that all valves in the entire circulatory system (Figure 1) are closed, and that a charge of liquid refrigerant under the pressure of its own vapor has been placed in the tank 10, a small amount of such liquid will pass from the tank 10 through the conduit 36 and the check valve 38 into the chamber 37 where it will expand and evaporate. Valve 33 serves to permit flow only from the tank to the expansion chamber. This vapor then passes through the conduit 39 into the cylinder 25 and forces the piston 26 to its extreme right-hand position shown in Figure 1. The piston 26 in moving to its extreme right-hand position forces the plug 32 to the right opening the valve 29 and, when shut-off valve 46 and pressure-control valve 47 have been opened, admits, through conduits 27 and 28 and valve 29 to the right-hand side of the piston 26, inert gas from cylinder 23 under pressure predetermined by regulating valve 41. This gas, when the pressure of refrigerant vapor in tank 10 and in cylinder 25 has become less than that of the inert gas from 23 against the right side of said piston, will force the piston to the left and in so doing will compress said vapor through the conduit 40 and check valve 41 (see Figure 1) into the upper portion of tank 10 above the liquid. Valve 41 serves to permit flow only from the cylinder 25 to the tank 10. Every time, therefore, that the piston 26 is moved from right to left under the influence of the inert gas from the cylinder 23, it compresses a volume of refrigerant vapor and returns it to the upper portion of the tank 10. This compressed refrigerant vapor, expanding in the tank 10 to a volume greatly exceeding that of the liquid which had flowed from said tank through conduit 36, augments the vapor pressure in tank 10 sufficiently to force liquid therefrom, via conduit 11, throughout the system.

When the piston 26 reaches its most leftward position, shown in dotted line in Figure 1, the guide rod 43 (Figure 2) is withdrawn sufficiently far from its cylinder 34 to enable the inert gas to enter the space 31 by way of cylinder 34 and passageway 35. While guide rod 43 has been withdrawn from its cylinder 34, guide rod 44, which is slightly longer than guide rod 43, is still partly within its cylinder. This serves to prevent rotation of the piston 26, thus assuring that guide rod 43 will re-enter its cylinder 34 when the piston 26 is returned to its right-hand position. The pressure of the inert gas in the space 31 exerts a force against the plug 32 forcing it to the left. This results in closing valve 29 and opening valve 42. The latter valve permits the inert gas to escape to the atmosphere under the control of an adjustable pressure relief valve 48. On the next rightward stroke therefore of piston 26, the piston may return to its extreme right-hand position shown in Figure 1, again simultaneously opening valve 29 and closing valve 42 (Figure 2). Adjustment of the pressure regulating valve 47

and/or the flow control valve 49 will serve to regulate the speed of the pressure booster device 24.

In order to provide a path of escape for the inert gas on the right side of the piston 26 as the latter is moved from left to right by the force of expanding refrigerant gas from chamber 37, a number of passageways are drilled or otherwise formed in the body of the pressure booster device. The first of these, bearing reference number 51, extends from the space to the right of piston 26 in a direction parallel to the axis of the piston. A second passageway 52 connects 51 to the passageway 53 which leads to valve 49. As the piston 26 is forced from left to right therefore, the inert gas will enter passageway 51, as indicated by the arrows in Figure 2, and thence through 52 and 53 to valve 49 which controls its release to the atmosphere.

The foregoing description of the operation assumes that initially all valves are closed and that the piston 26 is in its left-hand (dotted line) position (Figure 1), but such situation is not essential. If said piston stand initially in its right-hand position, valve 29 will be open and valves 46 and 47 may be opened initially to admit gas under pressure from cylinder 23 through valve 29 and cause the piston 26 to move leftward, increasing the pressure in tank 10 with the same effect as described above at page 7, lines 14 et seq. It is contemplated that use of the inert gas from cylinder 23 will be sufficiently infrequent that such cylinders readily may be replaced before they become completely exhausted, from supplies maintained either at suitable intervals or spare cylinders carried on or within the vehicle.

Other features of the system shown in the attached drawings are a dual purpose valve 45 connected to the interior of tank 10; and the pressure regulating valve 47 provided with a gauge 48. Before the system is filled with refrigerant, a pump is first attached to the valve 45 to withdraw air from the system. Then a refrigerant supply container is attached to valve 45 and the system is thereby charged with an adequate supply of refrigerant. A cap may also be provided to cover the inlet to valve 45 at all other times. In addition to the filling valve 45, a safety valve 50 is also provided which serves to vent the tank 10 in the event of pressure rise 50 therein beyond a predetermined level.

Refrigeration is accomplished by opening valve 14 and expansion valve 22 to allow part of the liquid refrigerant to flow from conduit 11 through the evaporator as more fully stated above at page 4, lines 12 et seq. By adjusting expansion valve 22 this system is adaptable to produce any of the wide range of temperatures from those below zero Fahrenheit required for frozen foods to those above freezing for fresh fruits, bananas, vegetables, and berries. Adjusting the pressure regulating valve 47 or the flow-control valve 49, either or both of which will affect the speed of the pressure booster 24, will adapt the system to meet any of the varying refrigeration loads occasioned by climate or by the varying temperatures of lading placed in the space to be cooled.

From the above it will be seen that the energy required to be supplied to this system via the pressure booster 24 driven by the high pressure gas from cylinder 23 will be much less than that which would be required in a system wherefrom the heat absorbed from the lading space is thrown away. The consumption of energy and 70

need for its replenishing are at a minimum; operation does not depend upon electricity or electrical connections being available nor require any supply of running water; the apparatus is unusually compact and simple, having few working parts; and there is no fire hazard present as would be the case in one or another of the conventional refrigeration systems known and in use today. Hence, the system is admirably suited for use in transportation conditions.

It should be further noted that operation of the pressure booster 24 is entirely automatic and the pressure in the system is maintained at a predetermined operation level by boosting the 15 pressure in tank 10.

In practice it is preferable that all the apparatus of the system, save the evaporator, will be positioned below the floor of the car for which the apparatus is to be used. This saving in lading space, plus the lowering of the center of gravity of the car, are marked advantages.

It will be apparent that the apparatus of this invention will find widespread use wherever low temperature refrigeration with a minimum energy input is required.

The drawings serve to illustrate only a preferred embodiment of this invention and obvious variations within the scope of the appended claims will be apparent to those skilled in the art.

30 I claim:

1. A refrigeration system comprising in combination: a pressure storage tank for refrigerant having space in the lower portion thereof for liquid refrigerant and space thereabove for gaseous refrigerant; means for automatically maintaining a predetermined pressure within said tank said means including a high pressure gas cylinder, a pressure regulating valve connected to the outlet of said cylinder, and a pump the cylinder of which is connected to said valve and to the said tank; an ejector of the jet pump type; a first conduit means connected to carry liquid refrigerant from the lower portion of said tank to the high pressure inlet of said ejector; an evaporator connected at its inlet end to the said first conduit means by means including a valve, and at the outlet end to the suction inlet of said ejector; and means including an elongated conduit for connecting the outlet of said ejector to the upper portion of said storage tank.

2. A refrigeration system comprising in combination: a pressure storage tank for refrigerant having space in the lower portion thereof for liquid refrigerant and space thereabove for gaseous refrigerant; means for automatically maintaining a predetermined pressure within said tank said means including a source of high pressure gas; a pump with a cylinder having a free piston slideably mounted therein, a refrigerant expansion chamber, means including a check valve connecting the lower portion of the refrigerant storage tank to said chamber permitting flow only from the tank to the chamber, conduit means connecting said chamber to said cylinder on one side of said piston, means including a conduit and a check valve connecting the same side of said piston to the upper portion of said storage tank permitting flow only from said cylinder to said tank, means connecting said source of high pressure gas to said cylinder on the other side of said piston, said means including a valve within said cylinder, means carried by said piston for opening said last mentioned valve when said piston is forced to one end of the cylinder by expanded refrigerant from said chamber, and

means for closing said last mentioned valve when said piston is forced to the opposite end of said cylinder by expanding gas from said source; an ejector of the jet pump type; a first conduit means connected to carry liquid refrigerant from the lower portion of said tank to the high pressure inlet of said ejector; an evaporator connected at its inlet end to the said first conduit means by means including a valve, and at the outlet end to the suction inlet of said ejector; and means including an elongated conduit for connecting the outlet of said ejector to the upper portion of said storage tank.

3. In a refrigeration system of the type in which a refrigerant evaporator is supplied with liquid refrigerant from a refrigerant storage tank, means for maintaining pressure on the system comprising: a source of high pressure inert gas; a pump with cylinder having a piston slidably mounted therein; a refrigerant expansion chamber; means including a check valve connecting the lower portion of the refrigerant storage tank to said chamber permitting flow only from the tank to the chamber; conduit means connecting said chamber to said cylinder on one

5

10

25

side of said piston; means including a conduit and a check valve connecting the same side of said piston to the upper portion of said storage tank permitting flow only from said cylinder to said tank; means connecting said source of high pressure inert gas to said cylinder on the other side of said piston, said means including a valve within said cylinder; means carried by said piston for opening said last mentioned valve when said piston is forced to one end of the cylinder by expanded refrigerant from said chamber; and means for closing said valve when said piston is forced to the opposite end of said cylinder by expanding inert gas from said source.
